Primary Examiner — Barbara Fox*(74) Attorney, Agent, or Firm* — Cantor Colburn LLP(57) **CLAIM**

We claim, the ornamental design for a confectionary, as shown and described.

DESCRIPTION

FIG. 1 is a perspective view of a confectionary, showing our new design in another exemplary embodiment; FIG. 2 is a side elevation view of the embodiment shown in FIG. 1, the opposite side view being a mirror image thereof; FIG. 3 is a top plan view of the embodiment shown in FIG. 1, the bottom view being a mirror image thereof; and, FIG. 4 is a front elevation view of the embodiment shown in FIG. 1, the back view being a mirror image thereof. References to “side,” “top,” “bottom,” “front,” and “back” in the Figure Descriptions are not necessarily meant to require any specific orientation of the article as viewed. A confectionary according to the claimed design may be used in any orientation.
